ICE BUCKET OR THE LIKE

Thomas F. Feeney, 6317 Liebig Ave.,
Bronx, N.Y. 10471

Filed Apr. 11, 1969, Ser. No. 16,695

Term of patent 14 years

Int. Cl. D7—99

U.S. Cl. D44—1

FIG. 1

FIG. 2

Des. 218,349

PAGE 2

FIG. 3

FIG. 4

FIG. 5

FIG. 6

FIG. 7

FIG. 8

FIG. 1 is a perspective view of an ice bucket showing my new design in closed condition;

FIG. 2 is a perspective view in open condition;

FIG. 3 is a top plan view in closed condition;

FIG. 4 is a side elevational view in closed condition;

FIG. 5 is a front elevational view in closed condition.

FIG. 6 is a rear elevational view in closed condition;

FIG. 7 is a reduced scale perspective view of an ice bucket showing another form of my new design, in closed condition; and

FIG. 8 is a perspective view thereof in open condition.

I claim:

The ornamental design for an ice bucket or the like, substantially as shown and described.
